UNITED STATES PATENT OFFICE.

EDGAR JOHN BLOOM, OF TIFFIN, OHIO.

GOLF TEE.

Application filed May 11, 1925. Serial No. 29,592.

To all whom it may concern:

Be it known that I, EDGAR J. BLOOM, a citizen of the United States, residing at Tiffin, in the county of Seneca and State of Ohio, have invented a new and useful Golf Tee, of which the following is a specification.

This invention relates to golf tees, one of the objects being to provide an inexpensive and compact device which is cheap to manufacture, light and durable and which will act efficiently to properly support a ball so that it can not become displaced by wind.

A further object is to provide a tee which can be easily carried without injury to the pockets or discomfort to the person carrying them, it being possible to reuse the articles time and again because of their sturdy construction.

20 A further object is to provide a tee which will rest firmly on the ground irrespective of any unevenness of the surface, it being possible to reverse the tee and thus prolong its period of service.

25 A further object is to provide a tee so constructed that when hit with a club the flight of the tee is greatly retarded by the atmosphere so that the tee will not travel very far and can be quickly recovered.

30 Another object is to provide a tee which will properly hold a ball even though the tee is mounted on an inclined surface.

A still further object is to provide a tee which permits the ready formation thereof 35 with no waste material.

With the foregoing and other objects in view which will appear as the description proceeds, the invention resides in the combination and arrangement of parts and in the 40 details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a front elevation of a tee set up for use, the position of a ball thereon being indicated by a broken line.

Figure 2 is a plan view of the tee opened out for use.

Figure 3 is a plan view of the tee prior to being opened.

Figure 4 is a face view of the closed tee.

Figure 5 is a view similar to Figure 4 showing a slightly modified structure.

Referring to the figures by characters of reference 1 designates a strip of stiff cardboard or other suitable material folded as at 2 and having the longitudinal edges of the folds recessed as indicated at 3. In the drawings angular recesses have been shown but it is to be understood that these recesses can be curved and can be deeper or shallower than illustrated, if preferred.

The two members of the tee are preferably scored or weakened transversely between their ends, as shown for example at 4 and 50 those portions of the two members located between the fold 2 and the scored or weakened portion 4 are fastened together by means of an adhesive, staples or any other suitable means. Thus the finished tee is 55 made up of end wings 5 and a third wing 6, this latter wing being twice the thickness of each wing 5.

Obviously the tee can be readily cut and fastened and can be produced at very low 60 cost and without waste of material. It can be carried flat in the pocket, it being possible to bundle together a number of them in any suitable way. The broad faces of the tee can be used for advertising purposes.

In using the tee the wings 5 are bent along the lines 4 relative to each other and to wing 6 until the three wings are disposed at approximately 120° to each other. This arrangement is illustrated in Figure 2. The tee is then placed with three of its points 7 in contact with the ground while the ball is mounted on the tee so as to rest upon and be centered by the three wings. When the ball is struck the tee is of course propelled 75 through the air but, because of its peculiar shape, it encounters considerable air resistance and, consequently, will fall to the ground close to the point from which it was driven. Thus it can be located easily, the wings 5 closed together, and the tee placed in the pocket and conveniently carried. The device can be placed with either of its edges uppermost and, because of its invertible nature can be used much longer than would otherwise be possible.

While the tee is preferably made of cardboard, it will be apparent that the same can also be made of other kinds of material if desired.

The peculiar structure of the tee enables the same to be thrust downwardly in tall

grass until brought to a firm footing on the ground.

In the drawings the adhesive used for holding together the closed portion of the fold has been indicated at 8. A staple used for fastening together this portion of the tee has been illustrated at 9 in Figure 5. Obviously other means than these may be used.

10 It is to be understood of course that, if desired, the material of which the tee is made can be waterproofed so as to withstand dampness when used during or after a rain or in the dew.

15 What is claimed is:

1. An invertible tee comprising radial wings, each longitudinal edge of each wing cooperating with the corresponding longitudinal edges of the other wings to provide 20 opposed ball receiving and centering recesses.

2. A tee comprising a strip of material folded upon itself and having free end portions, those portions of the strip between the 25 fold and the free end portions being connected together.

3. A tee comprising a strip of material folded upon itself and having free end portions, those portions of the strip between 30 the fold and the free end portions being connected together to form a wing, and said free end portions constituting wings, all of

said wings cooperating to support a ball upon the upper edges thereof.

4. A tee comprising a strip of material 35 folded and fastened together for a portion of its length to provide a wing made up of said fastened portion and additional wings made up of the free ends of the strip, said wings being bendable into and out of alignment at the center of the tee.

5. A one-piece tee comprising relatively movable wings radiating from a common center, said wings cooperating to support and normally retain a ball mounted on 45 either longitudinal edge thereof.

6. An invertible tee comprising relatively movable wings radiating from a common center, said wings cooperating to support and normally retain a ball mounted on the 50 tee when either longitudinal edge thereof is uppermost.

7. A collapsible invertible golf tee of waterproof material including radial wings, said wings cooperating along one edge to 55 support and normally retain a ball mounted thereon and cooperating at their other edges for firmly supporting the tee on a surface thereunder.

In testimony that I claim the foregoing 60 as my own, I have hereto affixed my signature.

EDGAR JOHN BLOOM.
